ATTORNEY

UNITED STATES PATENT OFFICE.

JAMES E. SMITH, OF MADISONVILLE, LOUISIANA.

CAN-OPENER.

1,280,321.

Specification of Letters Patent.

Patented Oct. 1, 1918.

Application filed July 9, 1917. Serial No. 179,590.

To all whom it may concern:

Be it known that I, JAMES E. SMITH, a citizen of the United States of America, residing at Madisonville, St. Tammany parish, 5 Louisiana, have invented new and useful Improvements in Can-Openers, of which the following is a specification.

This invention relates to combination tools.

10 The primary object of the invention is the provision of a tool in which is included tools of various kinds, arranged upon and within a common handle, said tools being so placed and arranged that any one may 15 be used while the remainder are housed within the handle in a manner to present a smooth and convenient grip.

Another object of the invention is the provision of a combination tool in which the 20 various tools combined are removable from the handle so that if they should become broken or otherwise useless they may be easily replaced.

A further object of the invention is the 25 provision of a tool which is of compact form and which may be easily and cheaply manufactured, thereby providing a set of useful tools at a small cost.

With the above and other objects in view 30 the invention consists of a common handle having formed upon one end a wrench, one of the edges of the said wrench forming a screw-driver, a hammer-head formed adjacent the screw-driver, and a can-opener, a 35 bottle-opener, and a corkscrew, all removably pivoted and housed flush within the said handle. The invention further consists of a knife-blade pivoted within the slot formed in the handle.

40 In the drawings;

Figure 1 is a perspective view of a combination tool embodying the present invention, the said tool being shown with all of its various attachments in an inoperative 45 position;

Fig. 2 is a longitudinal sectional view on the line 2—2 of Fig. 1, which is taken through the bottle-opener, the cutting blade of the can-opener, and the corkscrew.

50 Fig. 3 is a similar view on the line 3—3 of Fig. 1, illustrating the construction and mounting of the adjustable member of the can-opener;

Fig. 4 is a transverse sectional view on 55 the line 4—4 of Fig. 1;

Fig. 5 is a sectional view through the

upper portion of the can, illustrating the manner of opening the said can with the tool, the tool being shown in elevation.

Like characters of reference denote corresponding parts throughout the several views of the drawings.

In the drawings, the handle of the tool is shown at 10 and is of practically the same width throughout its length, one end of the handle having formed thereon toothed jaws 11 and 12 of an alligator wrench. The jaw 12 of this wrench is sharpened as shown at 13, for the purpose of providing a screw-driver, the said jaw 12 being slightly longer than the jaw 11 to more readily adapt it for this purpose. Along one edge of the handle and adjacent the jaw 12, there is formed a hammer-head 14, this head being located near the end of the handle for the purpose of providing sufficient leverage for its use.

The tool further includes a can-opener which comprises a cutting blade 15 and an adjusting member 16, a bottle-opener 17, a 80 corkscrew 18, and a pivoted knife blade 19.

The can-opener as stated includes the cutting blade 15, which is formed with a pivot 20, the said pivot being removably fitted within an opening 21 formed in the handle 10, while the cutting blade 15 is adapted to be housed within a depression 22 formed in the handle when it is in its inoperative position. In order that the cutting blade may be easily swung out of position from within the depression the said depression is formed along its curved edge with a slightly cut-away portion 23, for the purpose of permitting the insertion of the thumb nail or a sharp instrument beneath the cutting blade, which is beveled along its edge for that purpose. When the blade 15 is in position for use it projects substantially at a right angle from the handle, the opening 21 providing an edge for limiting the outward movement of this blade. In use this blade is designed to be run around the outer edge of the top of the can, and in order to accomplish this the tool is provided with a member 16 which co-operates with the said blade. This member 16 is formed at one end with a curved pointed portion 24, which is adapted to be inserted at the top of the can at the center thereof, and the blade 15 is then inserted in the top of the can near its outer edge and operated in the well-known manner (see Fig. 5).

For the purpose of providing for cans of different diameters the member 16 is adjustably mounted within a groove or depression 25 formed in the handle, upon a set-screw 26, this screw passing through a slot 27 formed in the member 16. The groove 25 is deeper at the end indicated at 28, in order to permit of the inclination of the member 16 when inserted within the can top. The opposite end of the groove 25 is provided with an opening 29, which is adapted to receive the point 24 to hold the member 16 within the groove when not in use.

15 The bottle-opener or bottle-seal remover 17, is removably and pivotally mounted within the handle 10 in a manner similar to the cutting blade 15, this bottle-opener being provided with a pivot 30 which is received within an opening 31 formed in the handle. The arm of this opener is formed at its end with a laterally extending hook portion 32, which is adapted to engage along the bottom edge of the bottle seal, 25 while the end of the handle 10 will rest upon the top of the seal and permit of its being lifted from the bottle in the usual manner. A depression 33 is formed in the handle 10 for the housing of the opener, a 30 laterally extending portion of this depression, which is indicated at 34, being provided for the reception of the hook portion 32. A thumb nail notch 35 is formed in the depression 33 for the manipulation of the 35 bottle-opener.

At its opposite end the handle 10 is provided with a removably pivoted corkscrew 18, the said corkscrew being provided with a removable pivot 36, which is received within 40 an opening 37 in the handle 10 after the manner of the tools previously described. The pivot 36 is formed with a lug 38, to which is secured the ordinary spiral corkscrew 39, a curve or depression 40 being 45 formed in the handle for the reception of the same.

The handle 10 is further provided with a slot 41 along one of its edges, and within this slot is pivotally mounted the knife blade 19, the said pivot being in the form of a set screw 43, by means of which the blade

may be removably pivoted within the slot. The usual knife-blade spring 44 is located within the slot, in order that this blade may be used in a manner similar to the ordinary 55 pocket knife.

From the above description, when taken in connection with the accompanying drawings, it is thought that the construction, operation and uses of the invention will be 60 apparent and that it will be therefore unnecessary to further describe it.

Having described the invention, what is claimed is;

1. A combination with a handle formed 65 with a depression in one face thereof and a substantially cylindrical open-sided socket communicating with the depression, of the cutting blade fitting within the depression, a transversely disposed cylindrical shank 70 carried by said blade, said shank fitting within the cylindrical socket, and an adjustable member carried by the handle and cooperating with the cutting blade.

2. The combination with a handle formed 75 with a depression in one face thereof, of an adjusting member comprising an elongated element slotted substantially throughout its length, a pin disposed transversely within, said depression and engaging the slot in, 80 the adjusting member, an engaging point carried by the adjusting member, and a cutting blade carried by the handle.

3. A combination with a handle formed 85 with depressions in one face thereof, one of said depressions communicating with a substantially cylindrical open-sided socket, of a cutting blade fitting within one of the depressions, a transversely disposed cylindrical shank carried by said blade, said 90 shank fitting within the cylindrical socket to provide a pivotal connection for the blade, an adjusting member disposed within the other depression, said member comprising an elongated element slotted, transversely throughout its length, a pin disposed 95 transversely within the last-mentioned depression, and engaging said slot in the adjusting member, and an engaging point carried by said member.

In testimony whereof I affix my signature.
JAMES E. SMITH.
